INSECT ELECTROCUTING TRAP

Robert D. Kahn, Rockville Centre, N.Y., assignor to
Fedtro, Inc., Rockville Centre, N.Y., a corporation
of New York

Filed May 22, 1967, Ser. No. 7,206

Claims priority, application Japan Dec. 3, 1966

Term of patent 14 years

(Cl. D22—19)

FIG. 1

FIG. 3

FIG. 2

FIG. 4

FIG. 1 is a front elevational view of the insect electrocuting trap;

FIG. 2 is a top plan view of the device;

FIG. 3 is a view rotated 45° from the view of FIG. 1 and having a portion of a strut broken away from clarity; and

FIG. 4 is a bottom plan view thereof.

I claim:

The ornamental design for an insect electrocuting trap, as shown and described.
